UNITED STATES PATENT OFFICE.

WLADYSLAW DUDEK, OF WINDSOR LOCKS, CONNECTICUT.

DESIGN FOR A CLOCK-CASING.

49,880.

Specification for Design.

Patented Nov. 14, 1916.

Application filed August 26, 1916. Serial No. 117,117. Term of patent 3½ years.

To all whom it may concern:

Be it known that I, WLADYSLAW DUDEK, a subject of the Emperor of Austria-Hungary, residing at Windsor Locks, in the county of Hartford and State of Connecticut, have invented a new, original, and ornamental Design for a Clock-Casing, of which the following is a specification, reference being had to the accompanying drawing, forming part thereof.

The figure is a perspective view of a clock casing showing my new design.

I claim:

The ornamental design for a clock casing as shown.

WLADYSLAW DUDEK.

Witnesses:

JAMES D. OUTERSON,
J. W. OUTERSON.
